UNITED STATES PATENT OFFICE.

FRANK BAUMAN, OF HONESDALE, PENNSYLVANIA.

SILK CLEANER.

Application filed August 17, 1927. Serial No. 213,674.

This invention provides an article for cleaning and evening silk thread in the preparation thereof for weaving to insure the production of a fabric possessing an even texture free from knots, projecting ends, fibers and particles of the preparation used in treating the threads to bind the filaments forming the components.

The invention supplies a cleaner which insures a uniform space between the cleaner elements, the latter being of metal which may be readily finished to present a straight edge and hardened to resist wear.

While the drawing illustrates a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawing hereto attached, in which,—

Figure 1 is a diagrammatic view of a silk thread cleaning machine embodying the invention.

Figure 2 is a front view of the rewinding mechanism.

Figure 3 is a top plan view of a cleaner embodying the invention.

Corresponding and like parts are referred to in the following description and designated in the several views of the drawings by like reference characters.

The mechanism embodies supporting members 1, 2 and 3, the member 1 receiving the thread rewinding mechanism including a spool 4 and a driver 5, such as a pulley or wheel. The member 3 carries a bracket 6 which is adapted to receive a spool 7 containing the silk thread 8 to be cleaned. The member 2 has the usual thread guide 9 attached thereto, and supports the cleaner proper which removes surplus preparation, knots and projecting ends of filaments or fibers in the cleaning of the thread as it is transferred from one spool, as 7, to the other, as 4. The members 1, 2 and 3 and the parts applied thereto are of well known construction and arrangement.

The present cleaner embodies a frame, a rod or pin and a cooperating blade. The frame is substantially of U-shape and com-

prises a base 10, and ends 11 and 12 projecting from the base 10 in the same direction. The end 11 is about half the length of the end 12 and has a threaded opening formed therein in which is fitted a plug 13. A small opening 14 is formed in the end 12 in position to register with a conical depression formed in the inner end of the plug 13. The rod or pin 15 has its ends tapered and fitted in the opening 14 and depression at the inner end of the plug 13. The rod or pin 15 usually consists of steel which is hardened and of uniform diameter throughout. The rod or pin 15 may be rotated to bring any desired element in operative position for the silk thread 8 to pass over.

The blade 16 is of a length slightly less than the rod 15 and its free end is beveled, as indicated at 17, with the result that opposite edges of the blade are of different lengths. The blade 16 is arranged with its long edge adjacent the rod or pin 15, and spaced therefrom a distance corresponding to the size of the thread 8 to be cleaned. The blade 16 is thin and of tempered steel to resist wear. One end of the blade 16 is bent at a right angle thereto, as indicated at 18, and is placed against the inner side of the end 12 to which it is secured by means of a bolt 19 or analogous fastening.

The thread, when spun and treated, is wound upon the spool 7. Preliminary to cleaning the thread the spool 7 is mounted in the bracket 6 and the end of the thread 8 is passed between the cleaning elements 15 and 16, thence over the guide 9 and is attached to the spool 4 so as to wind thereon when rotated by means of the driver 5. As the thread 8 is wound upon the spool 4 it is drawn between cleaning elements 15 and 16, and over the guide 9, and is unwound from the spool 7. The thread in its passage between the cleaning elements 15 and 16 has the surplus preparation removed therefrom, as well as knots, and any projecting ends of the fibers or filaments which form components of the threads. The cleaning elements 15 and 16 being of metal, may be finished to insure the opposing portions being absolutely straight, with the result that the space formed between said elements 15 and 16, is uniform throughout its length, thereby insuring the production of a thread which is uniform throughout, which is essential to the production of a silk fabric possessing a uniform texture free from knots and other objectionable

elements. It is observed that the rod or pin 15 may rotate, or be adjusted to present a new element opposite the blade 16, should it be found desirable for any cause.

5 Having thus described the invention, I claim:

1. A thread cleaner comprising a substantially U-shaped frame having its ends of uneven length, one of the ends having an opening, a plug threaded into the opposite end, a hardened metal rod mounted at one end in said plug and at the opposite end in the opening formed in the end of the frame, a hardened metal plate having an edge arranged 10 adjacent the rod and having an end portion bent and placed against the inner side of the

long end of the frame and means for securing the plate to the frame.

2. A thread cleaner comprising a substantially U-shaped frame, a rod, means pivotally 20 and adjustably connecting the rod to the ends of the frame, a blade presenting its edge to the rod and having an end portion bent at a right angle and in contact with an end of the frame, and having its free end beveled and 25 spaced from the opposite end of the frame and fastening means securing the bent end of the blade to the end of the frame with which it is in contact.

In testimony whereof I affix my signature.

FRANK BAUMAN. [L. s.]
